UNITED STATES PATENT OFFICE.

CHRISTOPHER C. MALTBY AND JOSEPH F. SABINE, OF CHICO, CALIFORNIA.

SURCINGLE.

SPECIFICATION forming part of Letters Patent No. 274,801, dated March 27, 1883.

Application filed January 19, 1883. (No model.)

To all whom it may concern:

Be it known that we, CHRISTOPHER C. MALTBY and JOSEPH F. SABINE, of Chico, in the county of Butte and State of California, have 5 invented certain new and useful Improvements in Surcings; and we do hereby declare the following to be a full, clear, and exact description of the invention, such as will enable others skilled in the art to which it pertains to make 10 and use it, reference being had to the accompanying drawing, which forms part of this specification.

Our invention relates to an improvement in surcings; and it consists in the combination 15 of a surcingle with a horn, which is attached thereto in any suitable manner, and suitable plates to prevent the surcingle from moving endwise, so as to enable the surcingle to be used as a lady's side-saddle, and thus dispense with 20 the great cost of saddles for ladies' use.

The object of our invention is to provide a 25 simple, cheap attachment, which can be used like an ordinary surcingle when so desired, but which, when desired, can have a horn or horns attached to it so as to allow it to be converted into a lady's side-saddle.

The accompanying drawing represents an 30 edge view of the upper portion of a surcingle embodying our invention.

A represents a surcingle of any suitable material, but which will preferably be made of leather or other strong material which is not likely to break while the surcingle is being used as a saddle. In order to prevent this 35 surcingle from slipping back and forth upon the horse's back, short metallic plates C, or of any other suitable material, are attached to the under side of the surcingle, and separated just far enough from each other to allow the surcingle

40 to pass over the top of the back. These plates or other suitable substances which are attached to the surcingle may be of any desired length, and serve to brace and strengthen the surcingle at those points where they are applied to them, and to stiffen it so that it cannot 45 slip back and forth over the top of the back. The top edge of the horse's spine will fit in between the plates, and owing to the rigidity imparted to the surcingle by the plates, 50 the surcingle can have no endwise movement

toward either side of the horse, no matter how great the weight that may be attached to it.

The one great objection to ladies' saddles is that they are so large and cumbrous and so very costly. This is especially so in those parts of 5 the country where the stores are few and far between. In order to do away with the use of side-saddles, and to provide a cheap and simple device which can be applied in an instant to any horse, we attach one or more 10 horns G to the surcingle, as shown, and which acts in the same manner as upon a side saddle. This horn may either be attached permanently to the surcingle or may be readily removed therefrom, so that the surcingle can 15 be used as an ordinary surcingle or for a saddle, as may be preferred. As the surcingle has no endwise movement toward either side of the horse, the horn gives all the support that is necessary and which would be received from 20 a saddle. If preferred, a stirrup may be also attached to the surcingle at any suitable point, and hang down in such a position that it can be used in the same manner as upon a saddle. This stirrup may or may not be attached to the 25 surcingle, as preferred. In order to protect ladies' clothing, the surcingle may be widened out at its top and along down one side to a sufficient degree to form a perfect protection to her clothing. This widened-out part may 30 be either removably attached to the surcingle or form a part thereof in any suitable manner.

Having thus described our invention, we claim—

1. A surcingle strap or band adapted to be passed around a horse's body, and provided with a horn or hook so as to adapt the surcingle for use as a side-saddle, substantially as set forth.

2. The combination of a surcingle, provided with suitable means for preventing it from moving endwise, with a horn which is applied to the surcingle, substantially as described.

In testimony whereof we affix our signatures in presence of two witnesses.

CHRISTOPHER C. MALTBY.
JOSEPH F. SABINE.
